UNITED STATES PATENT OFFICE.

IRVING J. FOLTZ, OF SAN FRANCISCO, CALIFORNIA.

GAS-BURNER.

1,307,294.

Specification of Letters Patent. Patented June 17, 1919.

Application filed July 12, 1918. Serial No. 244,548.

To all whom it may concern:

Be it known that I, IRVING J. FOLTZ, a citizen of the United States, residing at the city and county of San Francisco and 5 State of California, have invented new and useful Improvements in Gas-Burners, of which the following is a specification.

This invention relates to a gas burner, and particularly to a burner adapted for 10 generating and burning kerosene gas.

One of the objects of the present invention is to provide a simple multiple burner for domestic use, which can be easily installed in the fire box of a kitchen range or 15 stove, and adjusted when placed in position so as to fit any fire box, both for length and width.

Another object of the invention is to provide a plurality of gas generators operable 20 in conjunction with the multiple burner, which is adapted to handle kerosene, and, which may be used as single units if one or more should become inoperable, due to clogging or otherwise, or in unison if a greater 25 quantity of gas is being used.

Another object of the invention is to provide means for obtaining a proper mixture 30 of gas and air, and furthermore to provide means for distributing the gas to one or more of the burners, or to any portion of the same.

Further objects will hereinafter appear.

The invention consists of the parts and the construction and combination of parts 35 as hereinafter more fully described and claimed, having reference to the accompanying drawings in which—

Figure 1 is a side elevation of the burner.

Fig. 2 is a plan view of the same.

40 Fig. 3 is a cross section on line 3—3, Fig. 10.

Fig. 4 is a perspective view of one of the gas distributing valves.

45 Fig. 5 is a detail side elevation of the burner partly in section.

Fig. 6 is a front view of a needle valve control employed in connection with regulating the kerosene flow to the priming pan.

50 Fig. 7 is a cross section on line 7—7, Fig. 6.

Fig. 8 is an end view of a portion of valve 25 showing the handle on one of the valve rods.

Fig. 9 is an end view of the burner.

55 Fig. 10 is a central longitudinal section of

the same showing the piping connections through which kerosene is delivered to the gas generating tubes of the burner.

Referring to the drawings in detail, A indicates a casing interior on which is 60 formed a mixing chamber 2, and which also serves as the support for a plurality of burners, generally indicated at 3, 4, 5, 6 and 7. The casing also serves as a base member to the extent that it is adapted to rest upon 65 the grate bars of a fire box, and it also serves as a support for a plurality of generating tubes 8, 9 and 10. The burners shown at 3, 4 and 5 are formed of pipes or tubes which extend through the casing A 70 as shown in Figs. 1, 2 and 3. These tubes are slotted as at 11 to permit the escape of the gas and to form a series of small flames of any shape desired. The several tubes forming the upper burners 3, 4 and 5 are 75 turnably mounted in the casing, and to that extent may be adjusted to direct the flame in any direction desired. The burners shown at 6 and 7 are flat, and are provided with slot-like openings 12 in their outer 80 faces to permit the gas to escape there-through, and also to produce a series of flames on each side. The burners 6 and 7 are furthermore divided into upper and lower sections, and both sections may be operated in unison, or either section may be 85 operated independently of the other if desired. This is also true of the tube-like burners shown at 3, 4 and 5, that is, all the burners may be operated in unison, and any 90 one may be operated independently of the other.

It may be further stated that any portion of any tubular burner may be operated if desired. The generating tubes 8, 9 and 10 95 extend lengthwise of the tubular burners, and are positioned above the same. One end of each generating tube communicates with a manifold as shown at 14 to which kerosene is delivered by means of a pipe 15, the 100 amount of kerosene delivered to each generating tube being controlled by means of a needle valve 16, one for each tube. The opposite ends of the generating tubes are connected with pipes 17, and these pipes 105 are extended downwardly in front of the burner, and are then turned inwardly where they terminate in nozzles 18. These nozzles are positioned in direct alinement with a series of mixing tubes 19, there being one 110

for each pipe 17 and nozzle 18. The mixing tubes 19 are carried by the casing A, and they are slidably mounted therein to permit the said tubes to be moved endwise 5 with relation to the nozzles 18, thereby providing means for regulating the amount of air admitted with the gas.

Formed on the forward portion of the burner is a casing 20, which communicates 10 with the central burner tube 5. The forward face of the casing 20 is slotted as shown at 21 to permit a portion of the gas delivered to the tube 5 to discharge there-through. This gas is ignited, and the flame 15 produced is directed against the pipes 17, which, as previously stated, are connected with the respective generating tubes 8, 9 and 10. The flame projected from the casing 20 against the pipes 17 serves the function 20 of heating the gas during its passage from the generating tubes to the nozzles 18, or, in other words, heat applied at this point prevents cooling of the gas and condensation and precipitation of the same before 25 it discharges through the nozzles into the mixing tubes. The gas when heated produces considerable pressure, and therefore, discharges from the ends of the nozzles 18 with considerable velocity directly into the 30 mixing tubes 19. A jet action is, in this manner, obtained, and air is consequently drawn into the tubes 19, together with the gas, a proper mixture of air and gas being obtained by adjusting the tubes 19 with relation 35 to the nozzles, that is, endwise movements of each tube provides a means for increasing or decreasing the amount of air admitted.

The air and gas passing through the tubes 40 19 enters the mixing chamber 2 formed within the casing. It is here distributed to the several burners, or to one or more of the same as the operator may desire. This is accomplished in the following manner:

45 Slidably and turnably mounted in the lower portion of the casing are three valves such as shown at 25, 26 and 27. Each valve consists of an end disk 28 and a half section of a tube such as shown at 29. Each 50 valve is furthermore provided with a rod 30, and a handle extension 31, the rods 30 being projected through the front or door of the furnace not here shown to permit each valve to be readily manipulated by the operator.

55 By referring to Fig. 10 it will be seen that the mixing chamber and the side burners are divided into two compartments by means of a central partition wall 32, and it can also be seen by referring to this figure that one 60 of the valves, for instance 26, has been moved inwardly until the disk or head portion 28 of the same is in alinement with the central partition 32. This indicates that gas admitted through the co-operating mixing tube 19 will pass through the valve and

into one side of the casing only. This permits one-half of one of the side burners to be used, and if the valve is pulled clear back to the position shown at 29, both sides of one of the side burners can be operated. The 70 valve 26 connects with the side burners shown at 6, while the valve 27 connects with the burners shown at 7. By sliding either of these valves endwise it becomes possible to shut off all the gas to the respective co-operating burners; also to direct the gas to one-half of the same, or to direct the gas to the upper or lower sections of each of the side burners. It furthermore becomes possible to direct all the gas from the valve 26 80 to the burner shown at 7 or vice versa. This is due to the fact that each valve may not only be moved longitudinally, but also turned. For instance, by referring to Fig. 3, it will be seen that valve 27 is so turned 85 that the gas will escape in the direction of arrow a, thus supplying gas both to the upper and lower sections of the burner 7.

If it is desired to deliver gas to the upper half only, it is accomplished by turning the 90 valve to the position shown at 26, gas will then only be delivered to the upper half of the burner as shown by arrow b. A portion of the gas will also escape into a central chamber 40, and it may here be by-passed 95 into the upper chamber by turning the valve 25 forty-five degrees beyond the position in which it is shown in Fig. 3.

The several adjustments permit by-passing of the gas through the valves such as 100 shown at 25, 26 and 27, and permit any one of the generating tubes 8, 9 and 10 to be employed, or all of the same in unison, and all the gas from said generating tubes, or from one or more, may be directed to any burner 105 desired, for instance, all the gas supplied by the generating tubes may be directed to the upper burners 3, 4 and 5, or to any one of the same, by directing the gas to the lower chamber 40, and through a valve 25 to the 110 upper chamber. Again any one of the burners 3 and 4 may be partly closed, as each of the said burner tubes are provided with independent regulating valves as shown in 115 Figs. 4 and 5. This valve is exactly similar to the valves 25, 26 and 27, only that it is double in construction, a disk or head member 28^a being employed, and two half round sleeve sections 29^a. A gas is by-passed from the central chamber 2 to the burner tubes 120 3, 4 and 5 through an opening 50 formed in the lower and central portion of each respective tube. If the valve shown in Fig. 4, with which said tubes are provided, is turned with the half round section 29^a down, 125 it can readily be seen that the opening 50 will be closed, and that no gas will be admitted to said tube. Similarly if the valve is reversed in position, gas will be admitted. Again if it is desired to admit gas to one- 130

half of the tube only, it is accomplished by sliding the valve endwise, for instance, to the position shown in Fig. 5.

- In actual operation with a burner of the 5 character here described, installed in a fire box of a kitchen stove or like device, if it is desired to start the burners, it is accomplished by first filling the priming pan shown at 60 with kerosene from a pipe 61. 10 This pipe connects with an auxiliary tank 62, which is supplied from an exterior tank by means of a pipe 63. This tank is a measuring tank, and will not hold more kerosene than is just sufficient to fill the priming pan 15 60. The tank 62 is provided with two valves such as at 64 and 65. The valve 65 opens or closes the supply from pipe 63, while the valve 64 opens or closes the connection between the measuring tank and the priming 20 pan. Each of the valves 64 and 65 are provided with handles as shown, and each handle is provided with a projecting lug 66, which engages a rocking latch 67. When it is desired to fill the priming pan it is first 25 necessary to close the valve 65. This permits the latch to be moved into the position shown in Fig. 6 and therefore permits opening of the valve 64, the oil contained in the measuring tank will then escape through the 30 pipe 61 and enter the priming pan. It is then turned to closed position to permit opening of the valve 65. This valve is, however, not opened until the oil delivered to the priming pan has been ignited and all the oil 35 practically consumed. The generating tubes should then be sufficiently hot to generate gas and valve 65 may then be opened, the oil is then permitted to discharge through pipe 15, and enters the manifold 14 where it flows 40 to the respective generating tubes and is regulated by the needle valves 16. The oil thus admitted instantly turns into a gas and passes through the respective generating tubes and the pipes 17 to the nozzles 18 from 45 which it discharges directly into the mixing tubes, and finally enters the mixing chamber as described, a distribution of the gas being here determined by the position of the valves, the position of each valve being again 50 indicated by the position of the handles 31, as these may serve as indicators for this purpose, for instance, if it is desired to use the baking oven, it is probably only desirable to employ the burners on one side and to 55 direct the heat from said burners toward the oven. Again, if it is desired to cook only, it will probably only be necessary to employ the top burners 3, 4 and 5. Again, if it is desired to heat the water back in the fire box, 60 it may be desirable to employ one of the side burners only.

The provision of two or more generating tubes is also an important feature, as it provides ample means for generating a sufficient 65 quantity of gas to supply all the burners if

desired, or one or more if desired. It furthermore permits one or more of the generating tubes to be employed during an emergency, for instance, it might happen that one of the generating tubes might become 70 clogged, this may, therefore, be entirely removed for cleaning without disturbing the operation of the burner as a whole, as the remaining generating tubes will supply the quantity of gas required. 75

The device as a whole is simple and substantial, and can, therefore, be readily installed by any one and wherever desired. It is also so constructed that practically any size fire box may be fitted, to the extent that 80 spacer blocks may be inserted between the side burner and the main casing to widen it out if desired. Again, spacing blocks may be placed below the casing to lift it to any ordinary height desired. 85

I similarly wish it understood that the materials and finish of the several parts employed may be such as the experience and judgment of the manufacturer may dictate; also that ordinary gas may be admitted to 90 the nozzles 18 if it is not desired to generate the gas from kerosene as described.

By referring to Figs. 1 and 2 it will be seen that the upper portion of the casing 8 is slotted as shown at 65^a. These slots are 95 provided for the purpose of permitting a certain amount of the gas to escape through the casing and to maintain a flame at these points. This flame serves as a pilot light to the extent that it transfers the flame from 100 one end of the burner tube to the other, when one end of the burner only has been employed, for instance, with a valve positioned as shown in Fig. 5 only one end of the burner tube will operate, the flame will then burn 105 from the opening 65^a and from the openings formed in that end of the burner. If the valve is moved back to central position then gas will also escape through the opposite end of the burner. This gas will then be 110 ignited by means of the central flame passing out of the opening 65^a. The central burner 5 is provided for the purpose of heating the generating tubes and to confine this heat as much as possible by employing 115 a hood such as shown at 66^a. This hood confines the flame of heat about the tubes and thereby reduces the amount of gas required for this purpose, as comparatively little of this heat will escape, and only 120 enough will be required to maintain the generating tubes hot.

Having thus described my invention, what I claim and desire to secure by Letters Patent is—

1. A burner comprising a casing having a mixing chamber formed therein, a plurality of upper and lower burners connected with said chamber, means for by-passing gas from said chamber to any one of the burners 130

or to all in unison and means adapted to direct the gas to one end or to the entire length of the upper and lower burners.

2. A burner comprising a casing, a plurality of burners connecting with the upper portion of the casing, a plurality of burners positioned on each side of the casing, an upper and a lower mixing chamber formed within the casing connecting with the said 10 burners, and valves in the lower chamber adapted to direct the gas to one or both of the side burners, or to the upper burners, or to all the burners in unison.

3. A burner comprising a casing having 15 an upper and lower mixing chamber formed therein, a plurality of burners connecting with the upper chamber, an upper and a lower burner positioned on each side and connected with the lower chamber, and a 20 plurality of valves in the lower chamber adapted to direct the gas to one end or to the entire length of the upper and lower side burners, or to the uppermost of the side burners, or to the lowermost of the side 25 burners, or to all of the side burners in unison, or to one or more, or all the upper burners in unison.

4. A burner comprising a casing having an upper and lower mixing chamber formed 30 therein, a plurality of burners connecting with the upper chamber, an upper and a lower burner positioned on each side and connected with the lower chamber, and a plurality of valves in the lower chamber 35 turnably and longitudinally movable therein, adapted to direct the gas to one end or to the entire length of the upper and lower side burners, or to the uppermost of the side burners, or to the lowermost of the side 40 burners, or to all of the side burners in unison, or to one or more, or all the upper burners in unison.

5. A burner comprising a casing having a mixing chamber formed therein, a plurality 45 of burners extending through the upper portion of the casing having openings formed therein connecting with the mixing chamber, a valve slidably and turnably mounted in each burner, said valve adapted to direct 50 the flow of gas, so as to permit all or a portion of each burner to be operated.

6. A burner comprising a casing having a mixing chamber formed therein, a plurality 55 of burners extending through the upper portion of the casing having openings formed therein connecting with the mixing chamber, a valve slidably and turnably mounted in each burner, said valve adapted to direct the flow of gas, so as to permit all or a portion 60 of each burner to be operated, an upper and a lower burner secured on each side of the casing connecting with the mixing chamber, a valve interposed between the mixing chamber and each set of side burners, means for 65 passing gas through said valves, and means

for adjusting the position of said valves so that the gas may be directed to the mixing chamber, or to either set of side burners, or to one end or the entire length of the same.

7. A burner comprising a casing having a 70 mixing chamber formed therein, a plurality of burners extending through the upper portion of the casing having openings formed therein connecting with the mixing chamber, a valve slidably and turnably mounted in each burner, said valve adapted to direct the flow of gas, so as to permit all or a portion of each burner to be operated, an upper and a lower burner secured on each side of the casing connecting with the mixing chamber, 80 a valve interposed between the mixing chamber and each set of side burners, means for passing gas through said valves, means for adjusting the position of said valves so that the gas may be directed to the mixing 85 chamber, or to either set of side burners, or to a portion of the same, a third valve connecting with the mixing chamber, means for delivering gas to said valve, and means for adjusting the positions of the several valves 90 to direct the gas to any one of the upper burners, or to all in unison, or to any one of the side burners, or to all in unison.

8. A burner comprising a casing having a mixing chamber formed therein, a plurality 95 of burners extending through the upper portion of the casing having openings formed therein connecting with the mixing chamber, a valve slidably and turnably mounted in each burner, said valve adapted to direct the flow of gas, so as to permit all or a portion of each burner to be operated, an upper and a lower burner secured on each side of the casing connecting with the mixing chamber, a valve interposed between the mixing chamber and each set of side burners, means for passing gas through said valves, means for adjusting the position of 100 said valves so that the gas may be directed to the mixing chamber, or to either set of side burners, or to a portion of the same, a third valve connecting with the mixing chamber, means for delivering gas to said valve, means for adjusting the positions of the several valves to direct the gas to any 105 one of the upper burners, or to all in unison, or to any one of the side burners, or to all in unison, a plurality of generating tubes mounted above the burners, means for delivering oil thereto, means for delivering 110 gas generated to the mixing chamber, and means permitting operation of one or more of said generating tubes.

9. A burner comprising a casing having a mixing chamber formed therein, a plurality 115 of burners extending through the upper portion of the casing having openings formed therein connecting with the mixing chamber, a valve slidably and turnably mounted in each burner, said valve adapted to direct the 120 gas through said valves, and means

- flow of gas, so as to permit all or a portion of each burner to be operated, an upper and a lower burner secured on each side of the casing connecting with the mixing chamber, 5 a valve interposed between the mixing chamber and each set of side burners, means for passing gas through said valves, means for adjusting the position of said valves so that the gas may be directed to the mixing chamber, 10 or to either set of side burners, or to a portion of the same, a third valve connecting with the mixing chamber, means for delivering gas to said valve, means for adjusting the positions of the several valves to direct 15 the gas to any one of the upper burners, or to all in unison, or to any one of the side burners, or to all in unison, a plurality of generating tubes mounted adjacent one of the burners, means for delivering oil to any 20 one of said generating tubes, or to all in unison, a plurality of mixing tubes connecting with the mixing chamber, a nozzle mounted in alinement with each mixing tube, means for delivering gas generated to the respective 25 nozzles, and means for permitting the adjustment of the mixing tubes longitudinally with relation to the nozzles.
10. A burner comprising a casing having a mixing chamber formed therein, a plurality of burners extending through the upper portion of the casing having openings formed therein connecting with the mixing chamber, a valve slidably and turnably mounted in each burner, said valve adapted 30 to direct the flow of gas, so as to permit all or a portion of each burner to be operated,
- an upper and a lower burner secured on each side of the casing connecting with the mixing chamber, a valve interposed between the mixing chamber and each set of side burners, 40 means for passing gas through said valves, means for adjusting the position of said valves so that the gas may be directed to the mixing chamber, or to either set of side burners, or to a portion of the same, a 45 third valve connecting with the mixing chamber, means for delivering gas to said valve, means for adjusting the positions of the several valves to direct the gas to any one of the upper burners, or to all in unison, 50 or to any one of the side burners, or to all in unison, a plurality of generating tubes mounted adjacent one of the burners, means for delivering oil to any one of said generating tubes, or to all in unison, a plurality 55 of mixing tubes connecting with the mixing chamber, a nozzle mounted in alinement with each mixing tube, means for delivering gas generated to the respective nozzles, means for permitting the adjustment of the mixing tubes longitudinally with relation to the nozzles, and means for heating the gas during its passage through the generating tubes to the nozzles.
- In testimony whereof I have hereunto set 60 my hand in the presence of two subscribing witnesses.

IRVING J. FOLTZ.
